UNITED STATES PATENT OFFICE.

JOHN TWARDOWSKY, OF CHICAGO, ILLINOIS, ASSIGNOR, BY MESNE ASSIGNMENTS, TO
UNIVERSE CORPORATION, OF CHICAGO, ILLINOIS, A CORPORATION OF ILLINOIS.

COMPRESSOR.

Application filed September 30, 1921. Serial No. 504,526.

To all whom it may concern:

Be it known that I, JOHN TWARDOWSKY, citizen of Russia, residing at Chicago, in the county of Cook and State of Illinois,

5 have invented certain new and useful Improvements in a Compressor; and I do hereby declare the following to be a full, clear, and exact description of the invention, such as will enable others skilled in the art to 10 which it appertains to make and use the same.

My invention relates to compressors and in its general objects aims to provide simple, effective and entirely automatic means for 15 separating the compressed fluid from any lubricating oil which has been carried past the compressor proper, for returning such separated oil to the oil storage chamber, and for maintaining a desirable pressure back 20 of the piston of the compressor.

In operating fluid compressors, such as those forming parts of mechanical refrigerating systems, it is highly important that an ample supply of lubricant should be provided for the piston or other movable compressing member, so as to avoid the necessity of requiring attention to these parts in order to prevent undue wear. For this purpose it has been customary in fluid compressors 25 of the piston type to employ the crank casing as an oil storage receptacle out of which oil is splashed against the piston by the crank and the connecting rod. In practice, some of this oil will form a film on the bore 30 of the cylinder during the intake stroke of the piston and parts of the oil will then be carried with the compressed fluid into the discharge chamber. If left intermixed with the compressed fluid, the oil will interfere 35 with the proper operation of the expansion portion of the system and of the means for controlling the expansion, hence it is highly advisable that the entrained oil should be separated from the fluid before the latter 40 is discharged into the piping of the system. It is also advisable for the sake of economy that this oil should be returned to the crank casing so as to be used over again.

So also, it is desirable in compressors of 45 this general type to maintain some pressure continuously in the crank casing, so that the compressing stroke of the piston will not produce a partial vacuum in the crank casing, as such a partial vacuum would tend to 50 draw air through the bearings into this

casing. This is particularly true with mechanical refrigerating systems using ethyl chloride, methyl chloride or sulphur dioxide as the operating fluid.

In the copending application #473781 for 60 a patent on a compressor as filed May 31, 1921 by Hanson and Twardowsky, means have been shown for separating the entrained oil from the compressed fluid and for permitting the pressure of the latter to 65 discharge the separated oil into the crank casing at the end of each compression stroke of the piston through a return passage controlled partly by a needle valve and partly by the piston. With the arrangement there 70 disclosed, the return passage is opened to some extent with every reciprocation of the piston, regardless of the pressure in the crank casing. Consequently, it is difficult 75 to maintain a proper adjustment of the valve for this purpose, as an unduly restricted opening will hold back the oil, while an excessive opening may permit some of the compressed fluid to enter the crank casing 80 under substantially full pressure, thereby causing an undue back pressure in the crank casing and wasting the effect of some of the compressing. My present invention aims to overcome these difficulties and in general 85 aims to provide simple, easily adjusted and entirely automatic means for feeding the separated oil back into the crank casing and for maintaining a desirable amount of fluid pressure in the said casing. It also aims to provide simple and easily manipulated 90 means for adjusting the pressure thus maintained in the crank casing, and desirably aims to provide simple means for employing a balanced valve for this purpose. Still further and more detailed objects will appear 95 from the following specification and from the accompanying drawings, in which—

Fig. 1 is a central and vertical section through a compressor equipped with my invention.

Fig. 2 is a fragmentary horizontal section taken along the correspondingly numbered line in Fig. 1 and showing a portion of the oil return passage between the oil separator and the diaphragm-controlled needle valve 105 which automatically governs the returning of the oil.

In the embodiment of the drawings, I am showing my invention as applied to a compressor of the simple piston and cylinder 110

type, in which the compressing is effected by a piston 1 reciprocated in a cylinder 2 by a pitman 3 connected to a continuously rotating crank 4. I am also showing the discharge from the cylinder as controlled by a metal plate 5 normally pressed into its closure position by a spring 6 and forming a combined cylinder-head and check valve after the manner more fully disclosed in my copending application #494326, and am showing the discharge chamber 7 as connected to a separator chamber 8 containing a series of perforated baffles 9 having downwardly directed tongues 10 which catch the oil and permit the same to drip into the bottom of this chamber 8.

Between this separator chamber and the crank casing 11, I interpose a return duct including a diaphragm casing 12 and a pipe 23 leading from the latter to the crank casing. This diaphragm casing is desirably bolted to the bottom of the separator casing and desirably has a vertical bore 13 connecting the separator chamber with the interior 25 of the diaphragm casing. Slidably mounted in the bore 13 is a needle valve comprising a stem 14 and a tapering tip 15, the said tip having a seating portion tapered to correspond to the taper of a seat 16 towards which 30 seat the valve is continuously urged by a spring 17. The stem 14 of the needle valve is desirably hollow so as to partly house the spring 17, and has side portions cut away (as for example after the manner shown in 35 Fig. 2) to afford passages through which oil may flow down the sides of the bore 13 from the separator chamber 8 to the outlet into the diaphragm casing which outlet is controlled by the conical shoulder of the needle valve.

While continuously urged downward by the spring 17, the needle valve is also urged upward both by a spring 18 in the lower part of the diaphragm casing and by any 45 excess of pressure under the diaphragm 19 over that pressing against the top of the said diaphragm. For these latter purposes, I desirably fasten the diaphragm 18 to an upper pressure plate 20 which is recessed for 50 engaging the extreme lower end of the needle valve, and I also fasten the diaphragm to a lower pressure plate 21 arranged for receiving the upward thrust of the spring 18. Then I clamp the peripheral portion 55 of the diaphragm firmly and substantially air-tight between the flanges of the casing 12 so as to leave the central portion of the diaphragm free to be flexed upwardly or downwardly. I also provide suitable means, 60 such as an inlet 22, for connecting the lower portion of the diaphragm casing with the outer air.

Thus arranged, it will be obvious from Fig. 1 that the diaphragm is continuously urged upward by the combined pressure of

the spring 18 and the prevailing air pressure outside of the apparatus, while it is pressed downward by the combined pressure of the spring 17 and of the fluid in the upper portion of the diaphragm casing. As 70 this upper portion is connected by the tube 13 with the interior of the crank casing, the pressure in it will respond to that in the crank casing. Consequently, if the arrangement as described is so adjusted that the valve is substantially balanced with a predetermined difference in pressure between the outer air and the interior of the crank casing, a reduction of pressure within the crank casing will permit the air pressure 80 under the diaphragm to raise the latter, thereby permitting oil to be forced through the bore 13 and the pipe 23 by the pressure of the compressed fluid in the separator chamber 8. However, as soon as the resulting action raises the pressure within the crank casing sufficiently to overcome the distortion of the diaphragm which had opened the valve, the diaphragm will be flexed back to its normal position by the action of the spring 17, thereby closing the needle valve and shutting off the return connection between the separator chamber 8 and the crank casing.

To provide the delicate adjustment needed 95 for this purpose, I desirably interpose an adjusting screw 24 between the bottom of the diaphragm casing and a pressure plate 25 which receives the downward thrust of the spring 18. By turning this screw 24 100 (which is normally locked in position by a nut 26) I can readily adjust the effective action of the spring 18 so as to have the needle valve opened only when the pressure in the crank casing drops below a given amount. When thus adjusted, the action is entirely automatic, requiring no attention whatever on the part of the user.

However, while I have illustrated and described my invention as employed in connection with a certain type of compressor and as including certain desirable details of construction, I do not wish to be limited to this particular use of the same, nor to the details thus disclosed, it being obvious 110 that the same might be modified in many ways without departing from the spirit of my invention or from the appended claims.

I claim as my invention:

1. In a compressor having an oil storing casing, an oil separator interposed in its discharge passage, and means responsive to a predetermined pressure difference between the outer air and the interior of the said casing for forcing the separated oil into the 120 said casing.

2. In a compressor of the piston and cylinder type, a crank casing serving also as an oil storage receptacle, an oil separator interposed in the discharge passage of the 125

compressor, and means responsive to a predetermined reduction in pressure in the crank casing for forcing oil from the separator into the crank casing.

5 3. In a compressor of the piston and cylinder type, a substantially airtight crank casing serving also as an oil storage receptacle, an oil separator interposed in the discharge passage of the compressor, and means 10 responsive to a predetermined difference between the outer air and the interior of the crank casing for forcing oil from the separator into the crank casing.

4. In a compressor of the piston and cylinder type, a substantially airtight crank casing serving also as an oil storage receptacle, an oil separator interposed in the discharge passage of the compressor, means responsive to a predetermined pressure difference 20 between the outer air and the interior of the crank casing for forcing oil from the separator into the crank casing, and means operable from outside the aforesaid means for adjusting the pressure difference to which 25 the latter respond.

5. In a compressor of the piston and cylinder type, a crank casing serving also as an oil storage receptacle, an oil separator interposed in the discharge passage of the compressor, a passage through which oil may be returned to the crank casing from the separator by the pressure of fluid in the latter, and means responsive to a predetermined difference in pressure between the outer air 35 and the interior of the crank casing for controlling the said passage.

6. In a compressor of the piston and cylinder type, a crank casing serving also as an oil storage receptacle, an oil separator in-

terposed in the discharge passage of the 40 compressor, an oil return passage connecting the separator with the crank casing, a valve controlling the said return passage, and means responsive in action to variations in pressure in the crank casing for moving 45 the valve.

7. Mechanism as per claim 6, in which the said means comprises a diaphragm having its opposite sides respectively subject to external air pressure and to the pressure within the crank casing. 50

8. Mechanism as per claim 6, in which the said means comprises a diaphragm having its opposite sides respectively subject to external air pressure and to the pressure 55 within the crank casing, and adjustable spring means also acting on the diaphragm.

9. Mechanism as per claim 6, in which the said means comprises a diaphragm having its opposite sides respectively subject to external air pressure and to the pressure 60 within the crank casing, a pair of opposed springs also acting on the diaphragm and means for adjusting the action of the 65 springs.

10. Mechanism as per claim 6, in which the said means comprises a diaphragm having its opposite sides respectively subject to external air pressure and to the pressure 70 within the crank casing, a pair of opposed springs also acting on the diaphragm, and screw means adjustable from outside the valve for receiving the thrust of one of the springs.

Signed at Chicago, Illinois, September 75
17th, 1921.

JOHN TWAROWSKY.
